UNITED STATES PATENT OFFICE.

MARTIN ALBRECHT, OF FRANKFORT-ON-THE-MAIN, GERMANY.

MINER'S SAFETY-LAMP.

1,153,003.

Specification of Letters Patent. Patented Sept. 7, 1915.

Application filed November 24, 1913. Serial No. 802,819.

To all whom it may concern:

Be it known that I, MARTIN ALBRECHT, a citizen of the German Empire, residing at Frankfort-on-the-Main, in the county of 5 Hessen-Nassau and State of Prussia, Germany, have invented certain new and useful Improvements in Miners' Safety-Lamps; and I do hereby declare the following to be a full, clear, and exact description of the 10 invention, such as will enable others skilled in the art to which it appertains to make and use the same.

This invention relates to instruments for indicating changes in the gaseous conditions 15 of the atmosphere, and especially those designed to detect and show the presence of injurious gases in mines.

The present invention employs the heretofore known principle of a diffusion chamber 20 covered with a porous plate and connected with one limb of a U-passage filled with liquid so that, owing to the rise or fall in pressure produced in the diffusion chamber by gaseous changes, the level of the liquid 25 in the passage is displaced as is known from the physical principle of the barometer.

The heretofore known instruments could 30 not be readily carried about and used where most necessary to detect gaseous alterations in mines and were usually fixedly secured 35 in a vertical position so that they could not be shaken. In the present invention the instrument is so constructed that it can be carried about to detect gaseous changes without affecting its reliability in operation.

The drawing illustrates one practical construction of the invention in cross section.

The base 1 contains a suitable battery 2 which is inclosed in a vessel 3 having a cover 40 4 of insulating material. On the plate 4 are contact springs which connect the battery with an incandescent lamp 6. The lamp 6 has its neck loosely fitted in a socket 8^a; to hold the lamp in place its top presses 45 against a plate 11 of leather or felt attached to a reflector 10 suitably fixed within the upper end of an inclosing glass cylinder 9. A spring 8 in the socket 8^a is compressed by the insertion of the lamp neck therein and 50 if the lamp globe should be broken said spring will throw out the broken lamp so that the circuit is immediately broken. This is very important in case, in the presence of fire-damp, the glass-cylinder 9 and 55 also the lamp globe should be broken.

A diffusion chamber 12 is formed above

the reflector 10 and is covered by a diffusion plate 13 of suitable material sealed at its edges by a screw ring 22 and an elastic underlay 23. This diffusion chamber can 60 be brought into direct communication with the outside air, or with the interior of the lamp, by means of a valve 14 which can be actuated by means of a rod 24, lever 25 and push button 15.

Connected with the diffusion chamber between the lamp and the side of the glass cylinder 9 is a U-shaped passage 16 preferably formed in glass and of very small bore which contains a colored liquid 16^a that 70 under normal pressure stands at uniform height. The two walls of the limbs of the passage are each preferably of a special color, or distinctively marked for instance by colored glass beads 17 and 18. The limb 75 17 will hereafter be called the green side, and the limb 18 will hereafter be called the red side.

The pressure in the diffusion chamber 12 changes according to the alteration in the 80 gaseous state of the exterior atmosphere in known manner owing to the porous cover plate 13, and according to the pressure in chamber 12 the level of the liquid in the limbs of passage 16 varies.

When such lamp is brought into an atmosphere containing fire-damp, then the plus pressure accumulates in the diffusion chamber. Consequently, when fire-damp is present, the level of the liquid on the green 90 side will sink and the red side will rise. This is easily recognizable and will indicate the presence of as little as 3% of fire-damp. When equality between the outer air and the air in the diffusion chamber is attained, the 95 liquid in the red and green limbs will again assume a uniform level. In this manner there is provided an absolutely reliable indicator for fire-damp. In the presence of so called injurious gases which are heavier 100 than air (CO₂) the pressure in chamber 12 will be minus and the liquid will rise on the green side. The kind of exterior gases can therefore be determined with certainty.

By opening the valve 14 the level of the liquid in both limbs can be instantaneously brought to the same height. The glass cylinder 9 may be connected to a bottom plate 9^a which has a flange 9^b screwed onto an opposed flange 1^b on the upper end of the 110 casing 1. The lamp socket 8^a is attached to the plate 9^a the casing 1

may be uncovered so that the batteries may be readily removed or replaced.

The passage being beside the lamp the user can easily see in which leg of the passage the liquid is highest and be thus warned as to the condition of the exterior atmosphere.

The advantage of the small column of liquid in the passage consists in this that despite its smallness it gives a very effective signal automatically as soon as mine-damp occurs. The small amount of liquid in the passage does not darken the lamp much. Only a slit of a few millimeters is covered up by the liquid within the range of the lamp. But as soon as mine-damps occur which could cause the least peril, the liquid begins to move on account of the smallness of the column, similar to boiling water. The red liquid boils up and produces an extraordinarily intensive, flickering light which cannot be overlooked at all by the miner. As soon as for instance an excess of pressure takes place in the diffusion chamber, the column of liquid in the limb is pressed downward and as the volume is small it does not take long until the level of the liquid reaches the top of the passage and the gas can then escape through the other limb into the outer air. Not only by the passage of the gas bubbles through the left limb but also by the return of the liquid into the right limb after the escape of one gas bubble, the red fluid is shaken up in an intensive manner and an effective, flickering light is produced. This automatic indication of the change of gases is, of course, extraordinarily important for the miner cannot always watch the device in order to discover every movement of the same at once.

What I claim is:

1. The combination of a lamp, a member having a diffusion chamber adjacent said lamp, and a U-shaped passage carrying a fluid therein, said passage communicating at one end with said chamber, and interposed between the lamp and the spectator.
2. The combination of a lamp, a member having a diffusion chamber above said lamp, and a U-shaped passage connected at one end with said chamber, the limbs of said passage

being adapted to display distinctive colors, substantially as described.

3. An apparatus for the purpose specified, comprising a lamp, a casing having a diffusion chamber, and a U-shaped passage carrying a fluid therein, said passage being of very small cross section connected with said diffusion chamber and depending beside the lamp, and a liquid in said passage. 60

4. An apparatus for the purpose specified, comprising a base, a lamp attached thereto, a casing surrounding the lamp and having a diffusion chamber above the lamp, and a U-shaped passage carrying a fluid therein, 65 said passage being connected with said diffusion chamber and depending beside the lamp, substantially as described.

5. The combination of a lamp and a member having a diffusion chamber, and a U-shaped passage connected with said chamber and depending beside the lamp, and a vent valve in said diffusion chamber. 70

6. The combination of a base, a cylinder detachably attached to the base, having a diffusion chamber in its upper part, and a U-shaped liquid holding passage connected with said diffusion chamber, a lamp socket at the bottom of said upper portion, a lamp 75 removably fitted in said socket, a reflector below the diffusion chamber adapted to hold said lamp in the socket, and a spring in the socket for ejecting the lamp if broken. 80

7. In an apparatus for indicating changes in atmospheric pressure, the combination 85 with a casing and partitions dividing said casing into two closed chambers, of a passageway connecting said chambers and having its ends in open communication therewith; and a visual indicating medium carried 90 within said passageway, one of said chambers being a diffusion chamber whereby changes in atmospheric pressure will be communicated to said indicating medium through said diffusion chamber, substantially as described. 95

In testimony whereof I affix my signature in the presence of two witnesses.

MARTIN ALBRECHT.
